SAMUEL MARCUS, OF BROOKLYN, NEW YORK, ASSIGNOR TO MARKON MANUFACTURING CO., INC., OF NEW YORK, N. Y., A CORPORATION OF NEW YORK

DOLL'S-EYE CONSTRUCTION

Application filed March 6, 1926. Serial No. 92,729.

This invention relates to eyes for dolls, display figures and the like, preferably of the class in which the eyes are adapted to move or roll. One of the objects of the invention is to 5 provide extremely simple yet convenient means for so mounting a pair of artificial eyes on their connecting bridge as to avoid the necessity of using set screws or other such parts which cause trouble in assembling the 10 parts and are liable to become detached through use. Still other objects are to generally improve the construction of the eye sets, and to provide a decided advance in the art to which the invention relates.

15 These being among the objects of the present invention, the same consists of certain features of construction and combinations of parts to be hereinafter described and then claimed with reference to the accompanying 20 drawings illustrating a preferred embodiment of the invention, in which

Fig. 1 is a vertical central section on the line 1—1 Fig. 2, of the face portion of a doll, showing the improvements applied thereto;

25 Fig. 2 is a rear elevation of the improved doll's eye set showing it mounted in place in a head, which is shown in section;

Fig. 3 is an enlarged sectional detail on the line 3—3 Fig. 2, showing how each eye is 30 mounted in position in the set;

Fig. 4 is a section on the line 4—4 Fig. 2, showing the preferred means for anchoring the doll's eye set in position in the head;

Fig. 5 is a perspective view of the arms 35 which carry the weight which is adapted to roll the eyes; and

Fig. 6 is a sectional detail similar to Fig. 4 but illustrating another construction of mounting.

40 Referring to Figs. 1 to 4, inclusive, the face portion 10 of the head of a doll or the like may be composed of any suitable material, having eye sockets at which the right eye 11 and the left eye 12 slightly protrude, more or less in imitation of natural eyes. Each eye 11, 12 is preferably provided with a hemispherical metallic foundation shell 13, an outer thin transparent shell 14, and an intermediate thin opaque shell 15 on which the 45 iris is printed. The thin shells are prefer-

ably composed of celluloid. The shells 14 and 15 are preferably drawn over the foundation shell 13 and the eye structure assembled and made in the usual or any other suitable manner. Each eye 11, 12 is provided with a suitable eyelash 16 which protrudes from a slit cut in the thin shells 14, 15.

The eyes 11, 12 are mounted on and connected together by means of a wire supporting or bridge rod 17, so as to provide a pair of united eyes. In order to mount each eye on the bridge rod 17 so that the eyes may roll and be brought to open eye position or sleeping eye position, each eye 11, 12 is provided with a metallic back member 18 which may be formed integrally with the metallic foundation shell 13, said back member being provided at opposite sides, but extending within the eye structure, with perforated integral lugs 19, the perforations of which are in alignment. In an improved manner, to be later described, the eyes 11, 12 are rigidly held on the bridge rod 17 so that they may oscillate with said rod. For the passage of the rod 17 into the eye shell structures 11, 12, the adjacent walls of the same are provided with enlarged recesses 20, 21, respectively. By reason of the enlargement of the said recesses, there is permitted any desired angular adjustment of the eyes, with their lashes, in the eye sockets, which is accomplished by forcing the parts through more or less twisting the metal lugs 19 upon the bridge-rod 17. The back members 18 of the respective eyes 11, 12 are provided with slots 22, 23, each slot 50 extending in a plane substantially at right angles to the bridge rod.

The eyes are preferably provided with an actuating weight 25 in the usual manner, except that it is preferred to construct the weight in two solid sections 24, 26, these sections being spaced apart and connected together by a pin 27, the section 25 carrying the pin and the section 26 being held on the pin by the upsetting of the outer end thereof. Preferably the weight section 25 is provided with a cushion-buffer 28 inserted in a suitable socket in said section. This buffer may be of cork or any other suitable material for the purpose of eliminating noise when strik-

ing the inside of the chin of the doll or other head.

A piece of readily bendable wire is bent into suitable shape as illustrated, for example, in the perspective view Fig. 5, to provide arms 29 and 30, which are joined by a loop 31. This loop is inserted between the weight sections 25, 26, and the pin 27 passes through the loop whereby to secure the weight to the arms 29, 30. The arms 29, 30 are furthermore bent so as to provide open humps or rebent U shaped straddle members 32, 33 near the ends of the arms, one open hump being opposite the other one; that is to say, the gaps or openings in the humps are substantially in alinement.

The assembly or organization of the artificial eyes with the arms 29, 30 is accomplished by first passing the humps 32, 33 of the arms 29, 30 into the slots 22, 23, as shown clearly in Fig. 3, each hump being disposed between the perforated lugs 19 of the eye shell structures. This disposes the bottoms of the gaps or openings within the humps 32, 33 in line with the perforations in the lugs 19. The bridge rod 17 is then passed through the said perforations and the gaps in the humps 32, 33 so that the parts are assembled and may be adjusted to the position substantially as shown in Fig. 2. Thereby the eyes are securely held together and they are firmly attached to the arms 29, 30 from which the weight 24 is suspended. Beyond the humps or straddle members 32, 33, the extensions 33^a of the arms constitute stops to limit the rotation of the eyes to closed position.

As the loop-like humps 32, 33 are a trifle short in their extent away from the wire arms, the said humps have to be sprung slightly inward through the slots 22, 23 in order to let the bridge rod 17 pass through them. Consequently the rod 17 will act as a wedge or tie element and draw the humps into the slots 22, 23 and a binding relation thus be established between the humped portions of the arms and the bridge rod, whereby the eyes are firmly held upon the humped portions or straddle members of the arms, inasmuch as the back members 18 are caused to have a firm abutment against the wire arms. In the assembled device the U-shaped straddle members or humps 32 and 33, with the adjacent portions of the wire arms, constitute clamp members exerting a continuous resilient clamping pressure between the eyes and the bridge rod for maintaining the parts frictionally adjustably assembled. It results, therefore, that the eyes will always move in consonance with the oscillating movement of the weight 24, so that the proper rolling motion of the eyes will be obtained, and the eyes may be held in registration with the eye sockets in the face portion 10.

Some of the advantages of the present improvements not specifically mentioned are that the wires 29 and 30 are bendable to en-

able the assembly thereof and the eyes onto the bridge-rod 17, and to enable the adjustment of the eyes toward and away from each other, and that by bending the said wires forwardly or backwardly, the weight may be adjusted as desired with respect to the eyes. Furthermore, by pressing each wire 29 and 30 forwardly and the corresponding eye-shell backwardly, the gripping or binding action of the loop-like hump of the wire against the bridge-rod 17 will be sufficiently loosened to permit the eye-shell to be readily moved in either direction along the bridge-rod, and when this pressure of the wire and the eye-shell in opposite directions is released, the hump of the wire will be forced into frictional gripping engagement with the bridge-rod and thereby prevent any unintentional movement of the eye-shell along the rod.

To support the eye set reliably in the doll's head, the attaching means disclosed and claimed in co-pending application Serial No. 92,728 and now to be briefly described, may be resorted to, for example. An anchor member 34 is provided composed of suitable material, and it is provided with a supporting loop or post 35, which is provided with outwardly and rearwardly bent ends 36, all as more clearly shown in Figs. 1, 2 and 4. The loop or post 35 extends through an opening in the anchor member 34 and the bent ends thereof are extended outwardly along the forward face of member 34 and then rearwardly through the material of said member, to securely connect said parts together. The anchor member 34 is secured to the forehead portion of the head of the doll by means of a suitable filling 37 of glue between the anchor member 34 and the forehead of the doll, the glue extending around the edges of said member. The back of the doll's forehead is provided with an inwardly raised seat portion 38 formed up from the material of the doll's head and having a depression 39 slightly larger than the anchor member 34, so that the latter may be pressed onto the glue in said depression and firmly seated in proper position. The doll's eye set is provided with a hanger bracket 40 formed from a plate of sheet metal having parallel side flanges 41, and the edges 42 of the flanges may be serrated. The hanger bracket 40 is furthermore provided with flanges or ears 43 formed with slots 44. Spring legs 45 are provided, formed from a single piece of spring wire bent into bifurcated form. The connecting portion between the spring legs is inserted into a slit 46 cut in the metal hanger bracket 40, and the latter is clenched upon the said connecting portion so as to firmly secure the spring legs in such position that they will extend downwardly between the flanges or ears 43. The free ends of these spring legs 45 bear in a forward direction upon the bridge rod 17 on which the eyes 11, 12 are mounted,

thereby forcing the eyes forwardly to their bearing relation with the surfaces of the eye sockets.

The hanger bracket 40 is provided with an aperture 40^a and the supporting loop or post 35 passes through the same and extends rearwardly. A wedge 46^a is now driven into the rearwardly projecting portion of the supporting loop 35 and against the adjacent 10 surface of the hanger bracket. The wedge 46^a holds the doll's eye set and the hanger bracket firmly bound together, and the serrations 42 are caused to penetrate more or less the anchor member 34.

15 In the attaching means shown in Fig. 6, a screw-threaded headed pin 49 is passed through the anchor member 48 so that its head will bear upon the front surface of the anchor member 48, the screw-threaded portion of the pin protruding through the hanger bracket 47. Onto the screw-threaded end of the pin 49 there is then engaged a nut 50, which, when it is screwed home, will firmly secure the parts together. In both of 25 the illustrated forms of the invention, however, the doll's eye set may be detached from the head of the doll or the like whenever it is desired to adjust or reconstruct portions thereof.

30 It is obvious that the invention is susceptible of modification, as parts may be omitted, added, and substituted, and still be within the spirit of the invention without departing from the scope of the appended claims.

35 What I claim as new, is:

1. In a doll's eye construction, the combination of an eye provided with a slotted back member, a supporting rod adjacent the back member at a point opposite the slot, and securing means in frictional engagement with the back member looped into the slot and engaged about said rod to clamp the rod frictionally to said back member.

2. In a doll's eye construction, the combination of a pair of eyes, each provided with a slotted back member, a bridge-rod inserted through both back members at points forwardly of the slots, a weighted pair of arms having projections extending forwardly therefrom through said slots, said projections having rearwardly facing surfaces engaging the forward surface of the rod, and said arms also having parts engaging the back members to hold the eyes connected therewith and with the cross rod.

3. In a doll's eye construction, the combination of a pair of eyes, each provided with a slotted back member, a bridge-rod inserted through both back members at points forwardly of the slots, a weighted pair of arms, formed from a length of wire, open humps formed by bends in the wire inserted in said slots in engagement with said back members, and said rod passing through the openings 65 of the humps and bound with the arms.

4. In a doll's eye construction, the combination of an eye provided with a slotted back member, a supporting rod arranged adjacent the back member, a gravity control for the eye, and a part fixed to said gravity control 70 extending through the slot in frictional contact with parts of the back member and being connected with said rod to thereby hold the gravity control, the eye, and the rod assembled.

5. In a doll's eye construction, the combination of an eye provided with a slotted back member, a supporting rod adjacent said back member at a point opposite the slot, securing means comprising a member overlying the 80 back member and provided with an open hump inserted through the slot, said rod being engaged through the opening in the hump beyond the slot, the back member having parts to engage both the securing means 85 and the supporting rod, to thereby connect all of said parts together, and a weight carried by said humped member.

6. In a doll's eye construction, the combination of a pair of eyes each provided with a 90 slotted back member, a bridge rod extending adjacent both back members at points forwardly of the slots thereof, a weighted pair of arms formed adjacent their upper ends to engage the rear surface of the back members 95 and extend forwardly through the slots of the back members into connection with said rod, to hold the eyes connected therewith and with the rod.

7. In a doll's eye construction, the combination of an eye provided with a slotted back member, a supporting rod arranged adjacent one surface of the back member, and a clamp element engaging an oppositely facing surface part of the back member and extending through the slot of said back member into frictional engagement with a surface of the supporting rod which faces away from the back member, said clamp element being of a 105 springy character urging the rod against the back member to thereby adjustably connect the eye with the rod.

8. An eye set comprising a pair of eyes each having openings therethrough, a supporting rod for said eyes having its opposite 110 end portions extending through the openings of the eyes respectively, each eye having a further opening at the rear thereof beyond the supporting rod, and a gravity control member for said eyes comprising a weight 115 having a pair of arms projecting upwardly therefrom to the eyes respectively, said arms being formed of wire and each thereof being bent upon itself to provide a loop therein engaging the walls of the last mentioned 120 openings of the eyes and projecting through said openings and the supporting rod also extending through said loops in frictional engagement therewith to thereby hold the parts assembled.

9. In an eye set, an eye shell having oppositely disposed openings therein, a supporting rod for said shell extending through said openings, a gravity control for the eye engaging the cross rod intermediate said openings, said gravity control being of resilient material, said eye shell having a resilient part engaging the gravity control whereby to tightly frictionally retain said parts against relative movement, and the resiliency of the gravity control providing for manual flexing thereof to release said parts for adjustment upon occasion.

10. In a doll's eye construction, the combination of an eye, means for directly supporting the eye comprising members provided with friction means for tightly binding them together, one of said members being a member of the eye and having openings therethrough, a second of said members being inserted through an opening of the eye member in tight frictional engagement with the walls of said opening, said second member being formed to provide a seat therein, and another of said members engaging within the seat of the second member and being inserted through an opening of the eye member in engagement with the wall of said opening.

11. An eye set comprising a pair of hollow eyes spaced apart, a bridge rod to opposite end portions of which said eyes are connected, and the connection between at least one of said eyes and the bridge rod consisting of a back member carried by said eye having a slot therethrough, a pair of lugs formed upon the back member projecting from one surface thereof spaced apart in the direction of length of the bridge rod said lugs having aligned perforations through which the bridge rod extends, and a U-shaped clamp member having its looped end projecting through the slot and receiving the bridge rod therethrough in frictional engagement therewith, the legs of the U being bent into frictional engagement with the surface of the back member opposite the surface from which the lugs project.

12. An eye set comprising a pair of eyes, each having a pair of apertured lugs thereon spaced apart, a bridge rod extending between the eyes and through the apertures of said lugs, the lugs being bendable with respect to the remainder of the eyes to thereby facilitate adjustment of the eyes with respect to the bridge rod, and weight supporting members interengaging between the eyes and the bridge rod in the space between the lugs to hold the eyes against displacement from the bridge rod.
